UNITED STATES PATENT OFFICE.

CHARLES W. BRADLEY, OF ROCK RAPIDS, IOWA.

TAMPING-MACHINE.

1,047,738.

Specification of Letters Patent. Patented Dec. 17, 1912.

Application filed October 6, 1911. Serial No. 653,220.

To all whom it may concern:

Be it known that I, CHARLES W. BRADLEY, citizen of the United States, residing at Rock Rapids, in the county of Lyon and 5 State of Iowa, have invented certain new and useful Improvements in Tamping-Machines, of which the following is a specification.

This invention relates to tamping machines, and has for its object to provide a simple and an efficient machine especially adapted to be used for tamping plastic material, as for instance cement, mortar or clay in molds.

15 With this object in view the machine includes a frame adapted to be positioned over a mold, which may be of any desired structure, the said frame having journaled therein a shaft provided with a series of cranks.

20 Frames are mounted for vertical sliding movement upon the first mentioned frame and are located in the paths of movement of the said cranks when the cranks are moving in an upward direction, but when the 25 cranks begin to descend they pass beyond the ends of the movable frames so that the said frames and their attachments may drop. Spaced tamping rods are carried by each of the movable frames and tamping 30 heads are fixed to the lower ends of the said rods and are adapted to operate upon the material in the mold. Means is provided for holding the tamping rods and movable frames in elevated positions so that they 35 may not be lifted by the cranks when it is desired that the tamping operation shall cease.

For a full understanding of the invention reference is to be had to the following description and accompanying drawings, in which:—

Figure 1 is a side elevation of the tamping machine; Fig. 2 is a front elevation of the same; Fig. 3 is a perspective view of the 45 same; and Fig. 4 is a horizontal sectional view of the same on the line 4—4 of Fig. 2.

Corresponding and like parts are referred to in the following description and indicated in all the views of the accompanying drawings by the same reference characters.

50 The tamping machine consists of a frame 1 which is supported in elevated position above a mold 2. The mold 2 may be of any desired pattern or form. A shaft 3 is journaled upon the frame 1 and is provided with a belt wheel 4 around which a belt may

be trained for the purpose of rotating the shaft. The shaft 3 is provided with a series of cranks 5, preferably four in number, and these cranks are disposed in different directions about the axis of the shaft 3. Upon the pin 6 of each crank a roller 7 is loosely journaled.

Frames 8 are mounted for vertical sliding movement at the upper portion of the frame 1 and each said frame 8 carries two tamping rods 9, these rods being spaced one from the other. Tamping heads 10 are fixed to the lower ends of the rods 9 and are adapted to operate in the mold 2 at the opposite side 70 portions thereof. All of the rods 9 are provided on one side with a lug 11.

Plates 12 are hingedly mounted at their lower ends upon the lower portion of the frame 1 and extend up alongside the lower 75 portions of the rods 9. A rod 13 passes transversely through the upper portions of all of the plates 12 and is provided with stops 14 against which the sides of the said plates 12 bear. Coiled springs 15 are 80 threaded upon the rod 13 between the plates 12 and the next adjacent stops 14 and serve as means for resiliently holding the plates 12 against those stops 14 upon which they bear. The rod 13 projects at one end portion beyond the side of the frame 1 and the intermediate portion of a lever 16 is connected with the projecting end portion of the said rod. The lever 16 is fulcrumed to the upper portion of the frame 1 and the 90 lower end portion of the said lever is adapted to be engaged with a catch 17 that is located at the lower portion of the frame 1, whereby the lower end portion of the lever 16 is held away from the lower portion of 95 the side of the frame 1.

When the machine is in operation the lower portion of the lever 16 is positioned away from the lower portion of the frame 1 as last above described, and therefore the 100 upper ends of the plates 12 are held out of the paths of movement of the lugs 11. As the shaft 3 rotates the cranks 5 are carried around and the rollers 7 successively engage the lower portions of the frames 8 105 and lift the same. When the cranks 5 assume approximately vertical positions they pass from under the frames 8, whereby the said frames and their attachments are permitted to fall and the heads 10 tamp the 110 material in the mold 2. During the time that the said heads 10 are operating upon

the material, more material may be supplied to the mold so that the tamping operation may be continued during the placing of the material in the mold and during the process 5 of forming the article.

The vertically movable frames together with their attachments are of approximately the same weight and consequently the tamping operation will be uniform and the material 10 in the mold will be compressed to a uniform density. The successive action of the tamping heads will have a tendency to keep the material at or about the same level in the mold during the tamping operation. 15 When it is desired to interrupt the tamping operation without stopping the rotation of the shaft 3, the lower portion of the lever 16 is disengaged from the outer end of the catch 17 and the springs 15 force the upper 20 ends of the plates 12 toward the stops 14 and resiliently hold the upper or free ends of the said plates against the rods 9 when the parts are in the position as illustrated in Fig. 4. Consequently as the said lugs 25 and the rods 9 to which they are attached are lifted above the upper edges of the plates 12, the said lugs will seat upon the upper edges of the plates and the rods 9 and their attachments are prevented from falling 30 as the cranks 5 pass from under the frames 8 as above described. This is done when the article in the mold has been completed, so that the heads 10 are held in elevated positions, and the article may be removed 35 from the mold and the formation of another article continued.

The frames 8 are composed of side sections which are spaced from each other and the said sections are rectangular in side elevation and fit snugly about the upper portion 40 of the frame 1. The rods 9 are guided at the upper and lower portions of the frame 1 and consequently the upper portions of the said rods and the frames 8 are so disposed 45 about the upper portion of the frame 1 as to prevent the said frames 8 and the rods from binding during their reciprocatory movement with relation to the frame 1.

It will be observed that the lifting frames 50 8 project forwardly above the greater portion of the main frame, and the two frames are so relatively arranged that the lifting frames are guided by the main frame and thereby aid in maintaining the tampers in 55 a vertical plane during their operation. The lifting frames project over the drive shaft which is arranged upon the main frame, so that the full lifting strength of the drive shaft is utilized, and the tampers with the 60 lifting frames to which they are secured permitted to drop by gravity, so that the

weight of the frames and the tampers is utilized to pack the material in the mold.

It will be understood, of course, that the mold will preferably be so disposed beneath the tampers that the downward movement of the tampers will be arrested before the lifting frames strike the driving shaft, and injury to said shaft will be thereby avoided. It will, furthermore, be noted that the arresting plates or brakes by which the tampers are held in an elevated position are arranged between the tampers and extend up alongside the same, so that they do not project from the main frame or beyond the 75 tampers, and therefore are not liable to be struck by objects which may be brought near the apparatus, and injury to the said plates is thereby prevented.

Having thus described the invention what is claimed as new is:

1. A tamping machine comprising an elevated rigid main frame having upwardly and downwardly extending portions, tampers guided vertically by the upwardly and downwardly extending portions of the main frame, lifting frames secured to the upper ends of the tampers and projecting above and below the upwardly extending portion of the main frame in front thereof and slidably engaging the same, a driving shaft mounted on the main frame in advance of the upwardly extending portion thereof, and projections on said shaft adapted to engage the lower edges of the lifting frames. 95

2. A tamping machine comprising a supporting frame, vertically movable tampers mounted in said frame, means for effecting reciprocation of the tampers, arresting plates mounted on the frame between the 100 tampers and extending upwardly alongside the same to engage and hold them in an elevated position, and yieldable means for simultaneously moving all of said plates into and out of engagement with the tampers. 105

3. A tamping machine comprising a frame, rods mounted for reciprocatory movement in the frame, means for reciprocating the rods, lugs carried by said rods, plates hinged to the frame between the rods, a rod passing 110 loosely through the plates, stops carried by the last mentioned rod and bearing against the plates, springs interposed between the stops and the plates, and means for shifting the said rod. 115

In testimony whereof I affix my signature in presence of two witnesses.

CHARLES W. BRADLEY. [L.S.]
